(57) **CLAIM**

The ornamental design for a screwdriver handle, as shown and described.

DESCRIPTION

FIG. 1 is a perspective view of a screwdriver handle, showing my new design;

FIG. 2 is a front elevation view thereof, wherein the rear view is a mirror image;

FIG. 3 is a left side elevation view thereof;

FIG. 4 is a right side elevation view thereof;

FIG. 5 is a top plan view thereof; and,

FIG. 6 is a bottom plan view thereof.

The dotted lines indicate components for illustrative purposes only and form no part of the subject design.
